INCUBATOR

Frank E. Stover, Springfield, Ohio

Application May 3, 1934, Serial No. 723,734

6 Claims. (Cl. 119—37)

This invention relates to improvements in incubators, and has for its object to provide an incubator cabinet having a chamber therein providing a radiating surface, with means in the cabinet to cause the air therein to move and impinge upon the radiating surface.

It is an object of this invention to provide a cabinet in which trays of eggs may be arranged in stacks having means for reducing the air pressure in the cabinet, and means for conveying heat to the interior of the cabinet by radiation, and means to cause the air in the cabinet to cross the paths of the radiated heat.

It is an object of the invention to provide, in connection with an incubator cabinet, means for causing heat to be radiated into the cabinet, together with means for causing a circulation of the heat supply medium, and regulating the temperature of the heat supply medium.

It is also an object of the invention to provide, in connection with an incubating cabinet, a continuous chamber for the circulation of the heating fluid, together with means for causing the circulation of the fluid through the chamber and the introduction into the chamber of a definite, regulated amount of cooled air, the amount of cooled air admitted being determined mainly by the temperature of the heating fluid.

It is also an object of this invention to provide, in connection with an incubating cabinet, means for moving the air within the cabinet and applying moisture to the moved air, said means consisting of blades in the form of radially disposed troughs and rectangular channels, and means for delivering the moisture so it will be mixed with the air as it passes along the troughs and channels.

It is a further object to provide an incubator having a plurality of cabinets, with means for independently controlling the temperature, pressure and moisture in each cabinet, and a common source of heat for all of the cabinets.

It is a further object to provide, in connection with a cabinet, a vacuum system for producing in the cabinet a sub-atmospheric pressure and to regulate this pressure.

These and other objects and advantages will appear from the following description taken in connection with the drawings.

50 Referring to the drawings:

Figure 1 is a vertical, longitudinal section through one of the cabinets, looking from the left of Figure 2 with parts broken away and showing the egg tray supporting and turning means.

55 Figure 1a is a fragmentary side elevational

view of a part of the egg turning means shown in Figure 1.

Figure 2 is a view showing the rear side of the group of cabinets.

Figure 3 is an enlarged view of a portion of the structure illustrated in Figure 1 showing the upper rear corner of one of the cabinets, together with a part of the air circulatory system in section.

Figure 4 is a section on the line 4—4 of Figure 3.

Figure 5 is a section on the line 5—5 of Figure 3.

Figure 6 is a section on the line 6—6 of Figure 2.

Figure 7 is a vertical longitudinal section through the casing containing the cooling wheel chamber and the vacuum chamber on line 7—7 of Figure 6.

Figure 8 is a vertical section through the structure shown in Figure 1, with the front wall of the cabinet broken away to show the mechanisms contained therein.

Figure 9 is a vertical section of the top tray of one of the stacks of trays, on a line similar to line 9—9 of Figure 10 showing the egg turning rack therein.

Figure 10 is a section on the line 10—10 of Figure 1.

The present incubator structure consists of a plurality of cabinets arranged to form egg-containing chambers in which the temperature conditions are independently controlled for the application of heat and moisture to each chamber to and from a common source of heat, the air and moisture being distributed by power means driven from a common source of operative power.

The cabinet structure as a whole (Figure 1) has a front 1, a top 2, a bottom 3, sides 4 and partitions 5 separating the cabinet structure into various chambers. There is also a back 6. The front 1 is provided with an opening 7 for each incubating chamber. This opening has a suitable closure in the form of a door 7a. Within the interior of each chamber and adjacent the back 6 is an annular chamber 8 formed by means of a plurality of radiating plates 9. These plates are attached to the back, bottom, sides and partitions and form with these members the annular chamber. This annular chamber is rectangular in shape rather than round and corresponds to the general contour of the back of the main chamber.

At the bottom of the back and leading from the annular chamber 8 of each incubating chamber 55

ber is an air outlet 10. In the back 6, at the top of each chamber, is an air inlet opening 11. To each air outlet there is connected an outlet pipe 12 (Figure 2), which leads into an outlet main 13 which is closed at one end and provided at its other end with an opening 14 leading into a heating chamber 15 and a fresh air inlet opening 14a. Around the opening 14 is a fan 16, operated by a motor 17 supported on a bracket 17a on the cabinet. This fan is so constructed that it will take air from the outlet 13 and force it into the heating chamber, which has therein heating coils 18. Connected to the upper end of the heating chamber is a hot air pipe 19, which has one end connected to the heating chamber and it extends horizontally along the back of the cabinet adjacent the top.

Extending downwardly from the pipe 19 are a plurality of pipes 20 (Figure 2), one for each incubating chamber. To each pipe 20 is attached a rectangularly shaped housing 21 (Figures 1 and 3), which has an inlet 22, the purpose of which will be later described. Extending horizontally from the housing 21 is a pipe 23, which extends through the opening 11 into the chamber 8, and is provided with a closure 24 for closing the inner end thereof. The upper edge of this pipe, adjacent the closure, is provided with an opening 25 through which the air will pass into the chamber 8. A part 26 of each one of the plates 9 adjacent the opening 25 is shaped to form a seal between the inner end of the pipe 23 and the plate 9.

Pivotaly supported by the inner end of the pipe 23 is a shaft 27, which has attached thereto one end of an arm 28 by means of a screw 29. This arm extends longitudinally through the pipe 23 and terminates in the housing 21. On the other end of this arm are two forks 30, each of which has a slot 31 therein for receiving a pin 32 located on a sleeve 33.

Through this sleeve extends a rod 36. On this rod and adjacent one end of the sleeve 36 is a disc 34, suitably held against the end of the sleeve by means of a nut 38. Against the other end of the sleeve is a disc 35, held on the rod by means of a nut 37. This rod extends upwardly from the housing 21, through the pipe 19, and is guided by means of a guide sleeve 39 formed integral with and extending downwardly from the upper edge of the pipe 19.

On the shaft 27 on the outside of the pipe 23 (Figure 1) is an arm 40, which is adapted to be engaged by the upper end of a vertically disposed arm 41 pivoted on a bracket 42 attached to the inside of the back 6. To the free end of this bracket there is attached one end of a lever 43, which has swivelly attached to its other end one end of a screw 44 threaded into a bracket 45 supported on the top 2 of the incubator casing. The other end of the screw 44 has thereon a fork member 46, to which one end of a rod 47 is pivoted. This rod extends forwardly through the front of the cabinet 1, adjacent the top 2, and has thereon a head 48 by which the rod and screw may be rotated for adjusting the lever 43.

Extending between the lever 43 and the arm 41 is a thermostat 48a. The position of the lever 43 is determined by rotating the screw 44. The heat within the incubator chamber acts upon the thermostat 48a and causes the arm 41 to act upon the arm 40 to cause the arm 28 to move and manipulate the valves in the form of discs 34 and 35. The disc 34 is for the purpose of closing or restricting the passageway formed by the pipe 20,

while the disc 35 is used for closing or restricting the inlet passageway formed by the inlet 22. The positions of these discs are regulated by the thermostat 48a, and the temperature at which the thermostat will operate these discs is regulated by means of the screw 44 and the rod 47 and the head 48.

At the back of each incubating chamber (Figures 6 and 7) and supported by the back 6 is a casing structure 49, which has on one side thereof a cooling blower chamber 50 provided with an outlet 51 leading into a pipe 52 extending from the outlet 51 to the inlet 22 of the housing 21. This cooling blower chamber is provided with an inlet 53 for the purpose of admitting cool air into the chamber and into the housing for admission into the annular chamber 8. The bottom of the cooling chamber is provided with a closure 54. In this chamber is a cooling blower 55, supported on a shaft 56 mounted in suitable bearings 57 in a wall of the casing structure.

On the free end of the shaft 56 is a pulley 58 for receiving a belt by which the shaft and the cooling blower are rotated. There is also provided in this casing structure a vacuum chamber 59, which has an inlet 60 extending through the back of the incubator chamber for the purpose of withdrawing air from the incubator chamber and producing therein a reduced air pressure. In this vacuum chamber is a vacuum blower 61 supported on a shaft 62 in bearings 63 provided in a suitable part of the casing structure. On this shaft 62 without the vacuum chamber is a pulley 64, similar in shape, size and purpose to the pulley 58 and adapted to receive the same belt. This vacuum casing is provided with an outlet controlled by means of a gate or closure 65. By movement of this gate or closure the exhaustion of the air from the interior of the casing may be regulated.

In the casing structure between the cooling blower and the vacuum chamber (Figure 6) is a cylindrical chamber 66, through which a shaft 67 extends. One end of this shaft is reduced at 68 to form a shoulder 69. This reduced part 68 of the shaft is supported by means of bearings 70 located in one end of the cylindrical chamber 66. The other end of the shaft 67 is reduced at 71 to form a shoulder 72. Around this reduced part of the shaft and against the shoulder 72 is a bearing 73 supported adjacent the other end of the cylindrical chamber.

The end of the cylindrical chamber adjacent the bearing 73 is partially closed by means of a disc 74 attached thereto by means of screws 75. In the center of this disc is a hole 76 for the reduced part 71 of the shaft 67. Between the disc 74 and the bearing 73 there is a spring 77. On the end of the shaft 67, between the pulleys 58 and 64, is a pulley 78 which has on its periphery a groove to receive the belt 79 for operating the two pulleys 58 and 64. Adjacent this groove the pulley 78 is provided with an annular friction surface 80 for engagement by a friction gear 84, mounted on a shaft 81 supported in bearings 82 provided in brackets 83 attached to the back of the incubator casing structure, and also serving to support the casing structure 49.

The pulley 78 is rotated by means of the cone-shaped friction gear 84 which engages the friction surface 80. This friction gear is supported on the shaft 81 by means of a sleeve 85, which has on one end thereof, in engagement with the friction gear 84, a flange 86. The sleeve 85 is at 70

tached to the shaft 81 by means of a pin or some similar instrumentality 87.

On the end of the shaft 67 remote from the pulley 78 is a sleeve 88 (Figures 1 and 8), which 5 has extending radially therefrom a plurality of blades. Each blade consists of a radially and axially extending plate-like member 89. Each plate 89 has on one edge thereof a radially extending plate 90, which is perpendicular to the 10 axis of rotation of the rotary agitator and also perpendicular to the plate 89. On the leading edge of each plate 90 is a plate 91, which extends to and is united at one end with one end of a plate 92 attached to the trailing edge of an adjacent plate 90.

These plates 89, 90, 91 and 92 serve to form a plurality of troughs for the reception and dissemination of moisture. The trough adjacent the leading edge is indicated by the numeral 93, while 20 the trough adjacent the trailing edge is indicated by the numeral 94. Each trough 93 is provided with a cover 95 which extends from the tip of the blade more than halfway to the center of rotation of the rotary agitator. Each trough 94 25 is provided with a cover 95a which extends from the tip of the blade toward the center of rotation of the rotary agitator less than one-half the length of the blade. These covers form with the various blades rectangular channels through 30 which moisture is forced for distribution through the air, and regulate the flow of air from the center of the wheel to the periphery.

For the purpose of supplying moisture to the rotary agitator or fan adjacent the center thereof 35 (Figure 7), there is a pipe 96 which extends from the wheel to a point above the casing structure 49, and is provided with a funnel 97 from which it may receive water from a tank 98 through a spigot 99. The quantity of water delivered to 40 each funnel may be regulated according to the needs and requirements of the incubating chamber to which the moisture is to be applied.

In the top of the heating chamber 15 is a thermostat 100 (Figure 2) which has extending upwardly therefrom, through the upper wall of the chamber, a rod 101 connected at its upper end, in some suitable manner, to a lever 102 pivoted at the point 103. One end of this lever has thereon an adjustable weight 104, while to its other end 50 is attached one end of a rod 105, which extends downwardly for operating a switch 106 to make and break the contact of a circuit 107, which includes the heating coils 18. The details of the switch 106 form no part of the present invention. 55 The effective length of the rod 101 may be varied by the nut 101a. The responsiveness of the thermostat is controlled by adjusting the weight 104 on the lever 102.

In each incubating chamber and about midway between the front and the back (Figure 1) 60 is a plurality of uprights or posts 108, to which is pivotally attached a plurality of tray slides 109 at points 110. These tray slides are arranged in pairs and each pair is adapted to receive an egg tray and support it in the proper position for hatching purposes. Each tray slide is composed of a vertical part, which has a notch 111 therein and a horizontally disposed part 112 cut-away at the end adjacent the notch 111, as indicated by the numeral 113. The horizontally disposed parts 112 of each pair extend toward each other. For each tray slide there is provided at its front end, adjacent the notch 111, a slide shoe (Figures 9 and 10) which consists of a vertically 65 disposed part 114 having a part 115 hooked to

engage over the upper edge of the tray slide, and a horizontally disposed part 116 provided, at its front end, with a hole 117 to receive the bent end 124 of the egg turning frame.

The numeral 118 is used to designate the sides 5 of an egg tray, while its ends are designated by the numeral 119. One end has thereon, at each side, a tray lock 120 adapted to fit in a notch 111 in the tray slide. The front end of each tray is provided with a hole 121 adapted to receive the 10 egg turning frame, which is composed of side members 122 and transverse members 123. The front end of each side member is bent down at 124 to form a lug adapted to fit in the hole 117 in the tray slide shoe. There is also provided in 15 the front end of the tray, intermediate the locks 120, a handle 125 by which the tray may be manipulated.

The various slide shoes of one vertical series of 20 trays are connected by means of turning bars 126 connected to the shoes by means of pivots 127 (Figure 1). To the upper end of each turning bar is pivoted a lever 128. This lever is pivoted at 129 intermediate its ends to the upper end of the bar 126, while one end is pivotally attached at 130 to 25 one end of an arm 131 of a bellcrank lever pivoted at 132 on the standard or upright 108.

The other arm 133 of the bellcrank lever has pivoted thereto, at 134, one end of a link 135, the other end of which link is pivoted at 136 to 30 one end of an arm 137 of a second bellcrank lever, pivoted at 138 to the lower end of the post or standard 108. The other arm 139 of this second bellcrank lever is pivoted at 140 to one end of a link 141, the other end of which link is pivoted to 35 the turning bar 126 at the point 142.

The end of the lever 128 remote from the pivot 130 has therein a slot 143. In this slot works a pin 144 located on a rotating arm or disc 145. This disc is supported by a shaft 146 supported 40 in some suitable part of the incubator structure. Suitable means 146a and 146b is provided on the outside of the incubator for rotating this disc and the pin thereon. On the rotation of the disc the pin will cause the slot end of the lever to move 45 up or down, depending upon the direction of rotation. This structure, shown in Figure 1a, is illustrative of conventional means which may be utilized for the same purpose and forms no part of this invention.

Each of the three sets of trays is operated by 50 structure like the parts numbered from 126 to 141 inclusive. These parts are operated by disks rigidly mounted on the shaft 146 in the manner shown in Figure 1.

These parts are normally in the position so that 55 the trays are held horizontally. By rotating the shaft 146 the trays may be tilted. When the pin is in a horizontal line with the shaft the trays are in horizontal positions. By rotating the shaft 146 the pin causes the lever 128 to tilt, and thereby tilt the trays.

When the pin 144 engages the lever 128 at the 60 ends of the slot the lever 128 is given a longitudinal movement, thereby shifting the various slide shoes and at the same time shifting the egg-turning frames in the trays. This shifting takes place at the end of each tilting movement. When the shaft 146 is rotated the trays are first tilted without any movement of the eggs. When the pin reaches a position substantially in vertical alignment with the shaft at the end of the tilting, the shoes are moved, carrying with them the egg-turning frames.

A continued movement of the shaft 146 will 75

bring the trays back into a horizontal position, with the eggs properly turned. A further rotation will reverse the movement of the trays and also reverse the tilting movement of the trays, 5 and also reverse the movement of the egg-turning frames and the turning of the eggs. For the purpose of admitting fresh air to the various incubating chambers there is provided for each chamber an air inlet 147. Above the top tray 10 of each stack of trays is a protector screen 148, for catching solid matter, supported and operated in conjunction with the trays. In each chamber, at the sides, top and bottom thereof, are air vanes 149 for the purpose of controlling 15 the passage of air through the chamber. These vanes are supported by hinges 150 so that they may be moved with relation to the adjacent part of the chamber to regulate the extent of the space between the stack of egg trays and the 20 parts of the egg chamber. If these vanes stand out perpendicularly from their supporting members they almost entirely close the space around the tray stacks so that the air is forced through the egg trays. However, if these vanes are adjusted so they will lie more nearly flat 25 against the chamber walls or partition to which they are hinged, passageways are provided for the air around the stack of trays.

It will be understood that I desire to comprehend within my invention such modifications as 30 come within the scope of my claims and my invention.

Having thus fully described my invention, what I claim as new and desire to secure by Letters 35 Patent is:

1. In an incubator, a cabinet having a chamber therein, a power means on the cabinet, and means operated by the power means to apply a heating and a cooling fluid to the chamber to reduce the atmospheric pressure in the chamber 40 and stir the air in the chamber, said second-named means comprising a casing structure on the cabinet having a cooling wheel chamber, a vacuum wheel chamber and a fan supported by 45 the casing structure.

2. In an incubator, a cabinet, a heat exchange chamber for conveying a heat exchanging gas extending around the interior of the cabinet and closed against direct communication therewith, 50 said chamber having a heat conducting wall arranged to conduct heat between said chamber and the interior of said cabinet, positively acting means to move said gas through said chamber, and means in said cabinet for directing air and moisture in liquid form against said heat conducting wall prior to deflection thereof into the incubating space.

3. In an incubator, a cabinet, a heat exchange chamber for conveying a heat exchanging gas 55 extending around the interior of the cabinet and

closed against direct communication therewith, said chamber having a heat conducting wall arranged to conduct heat between said chamber and the interior of the said cabinet, positively acting means to move said gas through said chamber, means to cause the air in the cabinet to move and impinge upon said heat conducting wall, and means to supply moisture to the moving air before it impinges upon the heat conducting wall whereby any unvaporized moisture in 10 the air becomes vaporized said impinging means consisting of a rotary member of blade-like formation, the blades of which form troughs whereby moisture supplied to the moving air will be directed by the troughs into contact with said heat 15 conducting wall.

4. In an incubator, a cabinet having therein a plurality of incubating chambers, a heating gas passageway for all of the incubating chambers comprising an annular heat exchange chamber in each incubating chamber and having as one of its vertical walls a wall of the incubating chamber, means in the passageway to heat the gas therein and means for each incubating chamber to regulate the temperature of the gas 20 admitted to the heat exchange chamber therein.

5. In an incubator, a cabinet having therein a plurality of incubating chambers, a vertically positioned annular heat exchange chamber in each incubating chamber and extending therearound 30 and closed against direct communication therewith and having as one of its walls the wall of its incubating chamber, each heat exchange chamber having an inlet and an outlet, a heating chamber having an inlet connected to the heat exchange 35 chamber outlets and an outlet connected to the inlets of the heat exchange chambers, means to cause a heating gas to flow through a circuit including said heating chamber, means to supply a cooling gas to each chamber inlet, and thermostatic means in each incubating chamber to regulate the admission of heating gas and cooling gas to the heat exchange chamber therein.

6. In an incubator, a cabinet having therein a plurality of incubating chambers, a vertically 45 positioned annular heat exchange chamber in each incubating chamber having as one of its walls a wall of the incubating chamber, each heat exchange chamber having an inlet and an outlet, a heating chamber having an inlet connected to the heat exchange chamber outlets and an outlet connected to the heat exchange chamber inlets, means to cause a heating gas to flow through the circuit including said heating chamber, 50 means to supply a cooling gas to each exchange chamber, and adjustable thermostatic means in each incubating chamber to regulate the admission of heating gas and cooling gas to the heat exchange chamber therein.

FRANK E. STOVER. 60
